UNITED STATES PATENT OFFICE.

ERIK H. ALDEBORGH, OF NEW YORK, N. Y., ASSIGNOR TO CARL E. JOHANSSON, OF ESKilstuna, Sweden.

DIAMETER-GAGE.

1,401,119.

Specification of Letters Patent. Patented Dec. 27, 1921.

Application filed June 13, 1919. Serial No. 303,905.

To all whom it may concern:

Be it known that I, ERIK H. ALDEBORGH, a subject of the King of Sweden, and resident of New York, in the county of New York and State of New York, have invented a new and useful Improvement in Diameter-Gages, of which the following is a specification.

This invention relates to an improvement 10 in diameter gages with the object in view of providing such a device which is compact, accurate, simple to operate, and durable.

Another object consists in providing certain improvements in the form, construction and arrangement of the several parts whereby the above named and other objects may be effectively attained.

A practical embodiment of the invention 20 is represented in the accompanying drawing in which,

Figure 1 represents a plan view partly broken away, and

Fig. 2 represents a vertical section taken 25 in the plane of the line II-II of Fig. 1, looking in the direction of the arrows.

The instrument comprises a body portion, which is indicated by 1. This body may consist substantially of a flat plate 30 composed of some suitable material, such as cast iron.

In one end of the body, there is fashioned a substantially V shaped recess, which has straight side walls flaring outwardly. This 35 recess is denoted by 2, and its sides are surfaced with wearing plates 3 that are screwed to the body. These wearing plates are perfectly true and are preferably composed of some very durable material such as hardened 40 steel.

The body 1 also has a socket 4 which is formed therein and extends inwardly from the end of the recess 2. This socket has an annular shoulder 5. A plunger 6 is slidably 45 fitted in the socket 4 and is rearwardly reduced so as to have slidable engagement with the shoulder 5. A helical coil spring 7 is seated in the socket 4, between the shoulder 5 and the large outer end of the plunger 6, 50 so as to normally urge the said plunger outwardly toward the recess 2. A cross pin 8 is passed transversely through the inner end of the plunger 6 and is designed to abut the inner edge of the shoulder 5 so as to

limit the outward movement of the plunger under the influence of its spring.

A pin 9 is slidably mounted in the plunger 6 and is arranged to be fixed in any desired position in the said plunger by means of a set screw 10. The pin 9 is preferably composed of hardened steel.

An indicator hand 11 is pivoted at 12 in the body 1 and has a laterally projecting arm 13 that enters a slot 14 formed in the rear end of the plunger 6. A spring 11* 65 normally urges the hand to the left, Fig. 1. A graduated scale 15 is arcuately inscribed on the body 1 so as to register with the point of the hand 11. It has a zero point and degrees marked on each side of the latter.

For convenience, the body portion is provided with a hand grip 16.

In operation, a cylindrical or spherical object 17 of the size to which other articles being manufactured are designed to conform, is inserted in the recess 2 until it contacts with the plates 3. The set screw 10 is then released and the pin 9 moved in the plunger 6 until its point contacts with the object 17, while the hand 11 points to the 80 zero mark on the scale 15. The set screw 10 is then tightened to fix the pin in this position. Now, when it is desired to measure articles that have been manufactured, it is only necessary to place each article in the 85 recess 2 until it contacts with the plates 3. If the article is smaller than the standard, it will enter the recess 2 farther than the standard did and thereby press inwardly the pin 9. This movement of the pin 9 will 90 be transmitted to the hand 11, through the arm 13, and cause the said hand to move along the scale 15 to the right of the zero point. If the article being measured is larger than the standard 17, it will contact 95 with the plates 3 at points farther out than the standard, and will thereby permit the plunger 6 (and hence the pin 9) to be moved outwardly under the influence of the spring 7 before the pin 9 contacts with the article being measured. This condition will permit the hand 11 to move to the left of the zero point on the scale 15, under the influence of the spring 11*.

It will be observed that the scale 15 has a plus mark to the left of the zero and a minus mark to the right thereof, these marks indicating that the article being measured is either larger or

smaller than the standard according to which way the hand 11 moves from the zero point. In any particular case, a certain tolerance will be allowed which may be predetermined by the party in charge and indicated to the operator using the gage, in terms of degrees. If, in any case, the hand 11 does not move farther to the right or left of the zero point than the number of degrees indicated in the tolerance, the article will be accepted. But if the hand does move a greater number of degrees in either direction than is permitted by the tolerance, the article will be rejected.

It will be understood that various changes may be resorted to in the form, construction and arrangement of the several parts, without departing from the spirit and scope of my invention and hence I do not intend to be limited to the details herein described, except as they may be included in the claims.

What I claim is:

1. A device of the character described comprising, a body portion having an inwardly converging straight sided recess therein, a plunger mounted in the body at the inner end of the recess and normally

urged outwardly, a pin carried by the plunger at its outer end and projecting into the recess, a hand pivoted in the body and having an arm engaging the plunger, and a scale adjacent the free end of the hand, whereby the insertion of an article into contact with the sides of the recess will cause it to contact with the pin and thereby move the plunger to actuate the hand for indicating the size of the article.

2. A device of the character described comprising, a body portion having a converging recess therein, a plunger mounted in the body at the inner end of the recess and normally urged outwardly, a pin adjustably carried by the plunger at its outer end, a hand pivoted in the body and having an arm engaging the plunger, and a scale adjacent the free end of the hand, whereby the insertion of an article in the recess will cause it to contact with the pin and move the plunger to actuate the hand for indicating the size of the article.

In testimony, that I claim the foregoing as my invention, I have signed my name this 12th day of June, 1919.

ERIK H. ALDEBORGH.
